UNITED STATES PATENT OFFICE.

EBEN PERKINS, OF ST. JOHN, CANADA.

MACHINE FOR MAKING HORSESHOE-NAIL BLANKS.

SPECIFICATION forming part of Letters Patent No. 542,739, dated July 16, 1895.

Application filed June 7, 1894. Serial No. 513,790. (No model.) Patented in Canada October 9, 1894, No. 47,214.

To all whom it may concern:

Be it known that I, EBEN PERKINS, machinist, of the city of St. John, in the county of St. John, in the Province of New Brunswick, 5 Canada, have invented certain new and useful Improvements in Machines for Making Horseshoe-Nail Blanks, (patented in the Dominion of Canada October 9, 1894, No. 47,214,) of which the following is the specification.

10 My invention relates to improvements in machines for making horse-nail blanks; and the object of the invention is to provide a simple machine for making horse-nail blanks out of a continuous rod or coil of crucible or other steel; and it consists essentially of passing the rod, which is necessarily rectangular in cross-section, through a series of pairs of rolls, each alternative pair being horizontally and vertically journaled, and such 15 pairs of rolls being of increased diameters and situated at increased distances apart, proceeding from the end at which the rod enters, and having their peripheral faces constructed so as to properly act upon such rod, and the 20 machine being otherwise constructed and arranged in detail, as hereinafter more particularly explained.

Figure 1 is a perspective view of my machine as it will appear when complete, showing the rod passing through the rolls. Fig. 2 25 is a diagrammatic view showing a side elevation of the rolls and the form of the rod as it is passing through such rolls. Fig. 3 is a plan of the rolls, and also showing in the plan the form of the rod. Fig. 4 is a detail of a complete section of the rod as formed into horse-nail blanks.

In the drawings like letters of reference indicate corresponding parts in each figure.

40 A is the frame of the machine.

B B' are rolls secured on the vertical spindles b b' near their upper end. The spindles b b' are journaled in the horizontal bearing-box c, which is suitably secured to one side 45 of the frame of the machine. The rolls B B' are located in juxtaposition, as shown, and are operatively connected together, so that they rotate in opposite directions by the gear-

pinions D and D', which mesh with each other.

50 E is a set-screw for adjusting the vertical spindle b nearer to or farther from the spindle b', so as to regulate the distance between the rolls B B'. As this method of adjustment is a common one I do not show it in detail.

55 F F' are the upper and lower rolls, which are secured to the horizontal spindles f f', suitably journaled in the vertical bearing-box G. The rolls F F' are situated directly one above the other and are geared together 60 by the pinions H.

65 g are set-screws designed to adjust the position of the upper roll F in the usual manner. The rolls F F' are slightly larger than the rolls B B'.

70 I I' are the next succeeding rolls, which are secured on the end of the vertical spindles i i', suitably journaled in the horizontal bearing-box J. The rolls I I' are of increased diameter to the preceding pair, and are geared together by the pinions K K'. The roll I is adjusted by means of the set-screw J.

75 L L' are the next succeeding pair of rolls, which are journaled on the horizontal spindles l l', journaled in the vertical bearing-box M. The rolls L L' are of increased diameter to the two preceding, and are geared together by the gear-wheels N, and the upper roll L is adjusted by the set-screws m.

80 O O' are the next succeeding pair of rolls, which are secured on the ends of the spindles o o', which are journaled in the horizontal bearing-box P, and are geared together by the gear-wheels Q Q', and are of increased diameter to the preceding rolls. The roll Q is 85 adjusted by means of the set-screw p.

85 R R' are the next succeeding rolls, which are situated directly one above the other and secured on the ends of the spindles r r', journaled in the vertical bearing-box T. The 90 rolls R R' are geared together by the gear-wheels S S', and are of increased diameter to the two preceding rolls, and the upper roll is adjusted by means of the set-screws t.

95 U U' are the next succeeding pair of rolls, which are secured on the ends of the spindles

u u', which are journaled in the horizontal bearing-box *V*. The rolls *U U'* are geared together by the gear-wheels *W W'*, and are of increased diameter to the two preceding rolls. The roll *U* is adjusted by means of the set-screw *v*.

X X' are the next succeeding pair of rolls, which are situated directly one above the other, and are secured on the end of the spindles *x x'*, which are journaled in the vertical bearing-box *Y*. The rolls *X X'* are geared together by the gear-wheels *Z*, and are of increased diameter to the two preceding rolls. The roll *X* is adjusted by means of the set-screws *y*.

The spindles *b' i' O' U'* extend below their respective bearing-boxes, and have secured to them the gear-wheels *b' i' o' u'*. 2 3 4 are intermediate gear-wheels meshing with the gear-wheels *b' i' o' u'*, forming a chain of gear-wheels. The spindle *u* of the roll *U* also extends beneath the bearing-box *V'*, and has a beveled gear-wheel *u'*, which is driven by the beveled gear-wheel 5 on the countershaft 25 6, which is driven through the beveled gear-wheel 7 on the countershaft and beveled gear-wheel 8 on the main driving-shaft 9.

10 is a gear-wheel secured on the main driving-shaft 9 and meshing with the intermediate gear-wheel 11, which in turn meshes with the gear-wheel 12 on the end of the spindle *x'*.

The horizontally-journaled rolls are driven through a similar chain of gear-wheels and intermediate gear-wheels as the vertically-journaled rolls, and as this is apparent it is not necessary to go further into the description of the same.

It is sufficient to say that all the rolls are driven at the same rate of speed, whether 40 from the horizontal chain of gear-wheels or from the vertical chain of gear-wheels.

In Figs. 2 and 3 I show elevations and plan of the rolls in diagrammatic form. In the latter figure is shown the rolls *B B'*, between 45 which the rod 13 is first fed.

B' are a series of six grooves or recesses made directly across the peripheral face of each of the rolls *B B'*. These recesses are equidistant from each other on such peripheral face. Each of the rolls *I I' O O' U U'* are also provided with a series of grooves or recesses *I' O' U'* made directly across their respective peripheral faces. The width of each of these grooves or recesses is exactly the same 55 of all the rolls. The wheels shown in the plan are intended to act upon the side of the rods, so as to form the side of the head of the nail blank.

In Fig. 2, which shows an elevation of the 60 horizontally-journaled rolls it will be seen that all the lower rolls—namely, *F' L' R' X'*—are made perfectly cylindrical without any cross-recesses. The upper rolls *F L R* are made with a series of cross-recesses *F' L' R'* cutting directly across the peripheral face of

each roll. The grooves are situated equidistant from each other upon such peripheral faces. These latter rolls are intended to form the top of the head of the nail-blank. It will be noticed that the roll *X* has a series of six 70 *V*-shaped cutting-edges or projections *X'*, extending directly across the peripheral face and equidistant from each other. These are intended to form the indenture 13' to the rear of the head of each nail-blank as to the direction the nail-blank is moving. There are also a corresponding number of grooves *X'* made across the peripheral face in juxtaposition to the projection *X'*. 75

As hereinbefore described the rolls including both the vertically-journaled and the horizontally-journaled rolls increase in size from the point of entrance of the rod, which is in this instance shown at the left hand side of the figure to the point of exit of the completed 85 nail-blank. The distance between the rolls and the position in which the recesses of the rolls are set are so regulated that the heads will always come into the recesses as the rod passes through the rolls. As the rolls increase 90 in diameter from left to right it necessarily follows that the portion of the rod outside the head of the nail-blank is gradually squeezed or drawn out till it reaches its full extent at the last roll *X*, where the end of the nail-blank 95 is indented, as shown, preparatory to being severed. The head, however, will always remain the same width and depth and one side of the rod will remain perfectly flat, as indicated in Figs. 2 and 4. From this description 100 it will be seen that the nail-blanks may be formed continuously out of one rod or coil of suitable metal in the method hereinbefore described ready for the finishing-machine. It is preferably wound on a drum; but as this 105 forms no feature of my invention I do not describe the method in which it is wound.

It will, of course, be understood that in forming the recesses across the peripheral faces of the rolls that one side of each recess will 110 be preferably beveled off, so as to form the inner beveled portion of the beveled head. It will also be understood that in forming the rod into the nail-blanks the portions of the rod from which the heads are formed are not 115 reduced in the rolling-machine but left at their original size.

What I claim as my invention is—

1. A series of horizontally journaled pairs of rolls suitably driven, the upper one of each 120 pair of which is provided with a series of notches extending across its peripheral face and the lower rolls being perfectly cylindrical, the rolls being of increased diameter and situated at increased distances apart from the 125 point of feed of the rod, as and for the purpose specified.

2. The combination with the vertically journaled pairs of rolls, each pair of which has suitably formed notches formed across the pe- 130

ripheral faces, of the horizontally journaled pairs of rolls, the upper roll of each pair of which has notches extending across its peripheral face, and the lower roll of each pair being perfectly cylindrical, the horizontally journaled rolls being interposed between those vertically journaled and so arranged that the co-acting arcs of the horizontally journaled rolls are in direct alignment with

the co-acting arcs of the vertically journaled rolls, and all the rolls being of increased diameter from the point of feed of the rod and driven at a uniform speed, as and for the purpose specified.

EBEN PERKINS.
